UNITED STATES PATENT OFFICE

PAUL LANDROCK, OF ROCHESTER, NEW YORK, ASSIGNOR TO PHOTOSTAT CORPORATION, OF PROVIDENCE, RHODE ISLAND, A CORPORATION OF RHODE ISLAND

PHOTOGRAPHIC PRINT DEVELOPING APPARATUS

Application filed August 4, 1928. Serial No. 297,426.

My present invention relates to photography, and more particularly to the automatic or semi-automatic handling of photographic prints after exposure, such as the developing, fixing or washing thereof, and it has for its object to provide a simple, efficient, convenient and economical apparatus of this character particularly adapted for the treatment of prints in quantity as they come from a camera or exposing mechanism of the commercial type which is used to copy documents and relatively small objects of different kinds. The improvements are directed in part toward the provision of a fluid treating tray or container, the interior parts of which are made readily accessible for cleaning purposes; toward the provision of improved means for manipulating and positioning the print therein, and toward the provision of effective means for removing it quickly and without injury and without an excess of liquid adhering thereto. To these and other ends the invention resides in certain improvements and combinations of parts, all as will be hereinafter more fully described, the novel features being pointed out in the claims at the end of the specification.

In the drawings:

Figure 1 is a side view of a developing apparatus constructed in accordance with and illustrating one embodiment of my invention; Figure 2 is a top plan view thereof; Figure 3 is an end view showing the delivery end of the device;

Figure 4 is a plan view of the receptacle body or tray with the other removable and replaceable elements removed therefrom; Figure 5 is a plan view of the assembled apparatus with only the cover for the body thereof removed;

Figure 6 is a bottom view of the carrier that cooperates with the tray, and upon which the moving parts are mounted; Figure 7 is a top view of the same carrier; Figure 8 is a longitudinal section taken on the line 8-8 of Figure 5, but also showing the carrier in place in the tray, the moving parts being in normal position; Figure 9 is a similar section on the line

9-9 of Figure 5 showing the lid of the delivery opening raised;

Figure 10 is a transverse fragmentary section taken on the line 10-10 of Figure 8;

Figure 11 is a transverse fragmentary section taken on the line 11-11 of Figure 8;

Figure 12 is a side view of the tray alone with the detachable parts removed;

Figure 13 is a side view of the carrier for these parts shown alone;

Figure 14 is a transverse section through the carrier taken on the line 14-14 of Figure 13, enlarged;

Figure 15 is a transverse section through the carrier taken on the line 15-15 of Figure 7, the same being also enlarged, and

Figure 16 is a detail side view of the upper or submerging guide.

Similar reference numerals throughout the several views indicate the same parts.

I will first give a general description of the arrangements and major functions of the apparatus as a whole, and later describe the structure in detail pointing out the nature of my improvements more specifically.

Referring first more particularly to Figures 1, 2, 8 and 9, I provide a preferably rectangular and relatively shallow tray or receptacle 1 which is adapted to be enclosed or partially enclosed within a dark chamber beneath a camera or exposing apparatus. The latter is not shown as it is sufficient for the purposes of this invention to refer merely to the fact that photographic prints or exposed cut sheets of photographic film or paper may be fed mechanically or otherwise,

to the apparatus from a position above it or, in the present instance, in a downward direction. The print is received through an opening 2 at one end where its advancing edge first strikes the inclined portion 3 of a lower guide 4 and passes between the latter and a similar upper guide 5 spaced therefrom and from the bottom of the tray on which the lower guide rests. Both guides are preferably made of round, smooth, polished wires or bars laid parallel with each other as shown for instance in Figures 4 and 5. The print is indicated at P and is sufficiently stiff when dry

55

to project itself well within the guides. At this point it is taken up by a feeding device consisting in the present instance of rubber or other soft paddles 6 carried on shafts 7 and 8 turning in the direction shown by the arrows. The shafts are provided with sprockets 9 and are connected for joint movement by sprocket chains 10. The shaft 8 extends exteriorly and terminates in a crank handle 11 shown in Figures 1 and 2 by means of which the mechanism can be turned manually.

The paddles 6 are so arranged as to operate between certain bars of the upper guide 5 and to brush against the bars of the lower guide 4. When the print P intervenes, as shown in Figure 10, the paddles gently and yieldingly engage its surface and carry it along toward a delivery opening 12 at the opposite end of the tray accessible to the operator. This delivery opening is normally closed as shown in Figure 8 by a hinged lid or cover 13 pivoted at 14, and which has a limited opening movement, as shown in Figure 9. Carried by this cover in a manner hereinafter described in detail is a stop device for the advancing edge of the print consisting in the present instance of wire yokes 15 carrying loose rollers 16. The latter normally rest on the bottom guide and are shown with the print abutting them in Figure 8. When the print has been sufficiently treated (the paddles 6 also functioning as agitators for the liquid) the lid 13 is raised carrying the stops 15 out of the way and permitting further rotation of the paddle to convey the print up another inclined portion 17 of the lower guide 4 and out through the opening 12 where it is manipulated by the operator to its next position. The print is drawn over a rounded lip 18 at the mouth of the opening and cooperating therewith is a roller 19 carried by the cover 13, as shown in Figure 8. As soon as the operator has grasped the edge of the print the lid 13 is dropped not only to exclude light, but to allow the roller 19 to act as a squeegee in connection with the lip 18 and remove excess liquid from the surface. It may be said here that in the practice of my invention I mount the roller 19 in slots 20 or sliding bearings so that it is free from pressure from the weight of the lid, which latter rests on the edge of the tray and only the weight of the rollers 7 is imposed against the print.

The foregoing is the general construction and mode of operation of the apparatus which can readily be applied to and used in connection with a commercial or other type of camera by anyone familiar with photography. The chemicals used for the treatment of the print are quite active and one of the problems connected with the use of such apparatus is to keep it clean. As before indicated, one of the principal objects of the

present invention is to produce an apparatus, all parts of which are readily accessible for cleaning. To this end I so construct the device that all of the top and interior mechanism may be removed as a unit leaving the 70 pan 1 fully open as shown in Figure 4 with only the lower guide 4 remaining in place where it and the bottom of the tank can be readily scoured. The unit removed as previously described is shown in top and bottom 75 views in Figures 6 and 7. In fact I prefer to mount the lower guide 4 itself so that it may be removed if desired, for which purpose the front ends of the bars thereof are anchored in cleats or rails 21 secured to the 80 front end wall of the tray by screws 22. The opposite rear ends are anchored in the beforementioned squeegee lip 18 which is secured on the apron 23 at the rear end of the tray by screws 24.

The said removable unit embodies a carrier frame consisting of side walls or plates 24 that fit closely within the tray against the side walls thereof and resting on the bottom with bridge pieces 25 and 26 connecting them 90 at front and rear. These bridge pieces at their connecting points are reinforced by bracket plates 27 to give greater rigidity. At the forward end the bridge piece 25 has secured to its under side by screws 28 an L-shaped beam 29, the upstanding portion of which constitutes the rear edge of the print receiving opening 2. The other edges of the latter are formed by downwardly and inwardly turned flanges 30 on the rim of the 100 tray, the flange at the end shielding the advancing print from contact with the guide bar 21 as shown in Figure 8. The other portions of the flange 30 at the side constitute rocking abutments under which forwardly projecting portions 31 at the ends of the carrier plates 24 project and engage to hold it in place. The insertion of the carrier in the tray is effected by first making this engagement at the forward end and then 110 rocking the carrier downwardly at the rear until it fully enters the tray and rests upon the bottom thereof. As the carrier 24 is thus rocked into its cooperative position with respect to the tray, the projecting portion of 115 shaft 8 carrying the crank handle 11 is accommodated in a slot 49 in a side wall of the tray, which is preferably reinforced at this point by a plate 50.

Screws 28 which hold the bridge piece 25 120 and the beam 29 together also take into and hold in place a bar 32 in which the forward ends of the upper print submerging guide wires 5 are anchored. The rearward ends are similarly secured to a similar bar 33 held 125 by screws 34 in the bridge piece 26 so that, if desired, the upper guide may also be independently removed although this is not ordinarily necessary.

The horizontal portion of the beam 29 pro- 130

jects rearwardly beyond the edge of the bridge piece 25 to which it is secured to form therewith a rabbet or seat for the rear edge of a detachable panel 34 that covers the body 5 of the tray in a light tight manner. The rear end of this cover panel similarly rests on a similarly formed beam 35 associated with the rearward bridge piece 26 in a similar manner. The panel has an angularly and 10 downwardly projecting plate 36 secured to its under side at this point with which cooperates a downwardly turned flange 37 on the beams 35 to exclude light along the joint. This light baffle 36 extends down as far as 15 practicable toward the upper guide, and also excludes a majority of the light which would otherwise enter through the delivery opening 12 when the lid 13 is raised. The cover panel is applied by first engaging this rear 20 end thereof with the rearward bridge piece and then rocking it down forwardly to engagement at its forward end.

On its other three sides the panel plate 34 is provided with a continuous downwardly 25 turned flange 38 spaced from its edges, and one portion thereof acts as a light baffle to protect the seat of the panel at the forward bridge piece 25. The side flanges 38 are spaced as best shown in Figures 5 and 10 30 from flanges 39 at the side edges of the panel and the two of them fit down upon opposite sides of inwardly turned horizontal flanges 40 at the top edges of the side plates 24 of the carrier so that the intervening surface of the 35 panel lies flat upon these carrier flanges 40 and light is effectively excluded. The outer flanges 39 also embrace the tray itself as is clearly shown in the figures.

Returning again to the delivery end of the 40 tray, the lid 13 for the delivery opening 12 is, as before stated, pivoted at 14, which pivots are carried by the carrier 24 in the region of the bridge piece 26 and the brackets 27 so that this lid is also removed bodily from the 45 tray with the carrier. Its opening movement is limited by a slotted link 41 pivoted on a bracket 42 on the under side thereof at 43. The slotted portion of this link slides upon a pin or abutment 44 projecting inwardly at the side from one of the carrier plates 50 24. This function is illustrated by a comparison of the positions of the parts in Figures 8 and 9.

The stop yokes 14 previously referred to, 55 are carried rigidly at the lower edge of an angular plate 45 which also acts as a light guard. The other substantially horizontal angular portion of this plate is pivoted at 46 to swing freely from the lower edge of a 60 bracket plate depending vertically at 47 from the under side of the lid 13. This offset pivotal attachment of the stop plate 45 causes it to normally swing rearwardly at an angle when the lid 13 is in closed position, as shown 65 in Figure 8. In such position the stop yokes

15 carried thereby occupy positions in recesses indicated generally at 48 (see also Figure 4) in the inclined portion 17 of the lower guide 4, which depressions are formed by bending inwardly alternate groups of the 70 wires constituting the guide. In this way the stop is sure to intercept the advancing edge of the print P, as shown in Figure 8. But the stop plate 45 is positioned at all times by engagement with the pin 44, and when 75 the lid 13 is raised the stop plate rides against the pin, and is swung rearwardly to a vertical position as shown in Figure 9. The yokes and rollers 15 and 16 are similarly 80 carried rearwardly away from the opening 12 and away from the lower guide so that there is a combined upward and lateral displacing movement that gives greater clearance for the passage of the print up the incline 17 and out through the opening 12, than 85 would otherwise be afforded.

A photographic print developing or treating apparatus made in accordance with my invention may be constructed throughout substantially entirely of non-corrodible sheet 90 metal; it is simple in construction and manipulation, and all parts are ready accessible for cleaning purposes.

I claim as my invention:

1. In a photographic developing apparatus, the combination with a tray having an opening for the introduction of an exposed print at one end, of an upper submerging guide for the prints spaced from the bottom of the tray and a quickly and easily removable and replaceable carrier fitting within 95 said tray and supporting said guide and also carrying a cover for the tray.

2. In a photographic developing apparatus, the combination with a tray having an opening for the introduction of an exposed print at one end, of an upper submerging guide for the prints spaced from the bottom of the tray, a quickly and easily removable and replaceable carrier fitting within 105 the tray and supporting said guide, and a liquid agitating device also supported by the carrier and movable bodily therewith.

3. In a photographic developing apparatus the combination with a tray having an opening for the introduction of an exposed print at one end, of an upper submerging guide for the prints spaced from the bottom of the tray, a quickly and easily removable and replaceable carrier fitting within the tray and supporting said guide, and a print feeding device also supported by the carrier and movable 115 bodily therewith.

4. In a photographic developing apparatus, the combination with a tray having an opening for the introduction of an exposed print at one end, of an upper submerging guide for the prints spaced from the bottom of the tray, a quickly and easily removable and replaceable carrier fitting within the tray 125

and supporting said guide, a liquid agitating and print feeding device supported by the carrier and movable bodily therewith, and a displaceable cover panel for the tray also supported by the carrier.

5. In a photographic developing apparatus, the combination with a tray having an opening for the introduction of an exposed print at one end, of a feeding device for the prints operating within the tray, and a quickly and easily removable and replaceable carrier fitting within the tray and upon which the feeding device is supported for removal as a unit therewith.

10 6. In a photographic developing apparatus, the combination with a tray having an opening for the introduction of an exposed print at one end, of a carrying frame fitting closely within the tray and embodying side plates resting on the bottom of the tray, and an upper submerging guide supported by the carrying frame and thereby spaced from the bottom of the tray.

15 7. In a photographic developing apparatus, the combination with a tray having an opening for the introduction of an exposed print at one end, of a carrying frame fitting closely within the tray and embodying side plates resting on the bottom of the tray, a shaft turning in the said side plates of the frame and terminating in an exteriorly arranged crank portion and print feeding devices within the tray operated by the shaft, a side wall of the tray being slotted to accommodate the shaft and permit the removal and replacement of the carrying frame.

20 8. In a photographic developing apparatus, the combination with a tray adapted to receive photographic prints, and having inwardly turned flanges on opposite walls, of a cover panel having pairs of relatively spaced downwardly projecting flanges at its edges fitting on the inturned flanges of the tray, the portion of the cover panel between the flanges resting flat upon the flanges of the tray.

25 9. In a photographic developing apparatus, the combination with a tray adapted to receive photographic prints and provided with a bridge piece, of a cover at one end of the tray pivoted adjacent to the bridge piece to afford limited access to the interior and a cover panel covering the body of the tray and cooperating with the bridge piece, said cover panel being provided adjacent to the latter with a depending light guard.

30 10. In a photographic developing apparatus, the combination with a tray adapted to receive photographic prints and provided with a bridge piece having a depending flange on its under side, of a cover at one end of the tray pivoted adjacent to the bridge piece to afford limited access to the interior, and a cover panel covering the body of the tray and cooperating with the bridge piece, said cover

35 panel being provided adjacent to the latter with an angular depending light guard flange cooperating with the edge of the flange on the bridge piece.

40 11. In a photographic developing apparatus, the combination with a tray having a print receiving end and print delivery end, of a quickly and easily removable and replaceable carrier associated with the tray, a cover panel on the carrier covering the body of the tray and a cover hinged to the carrier at the delivery end of the tray and adapted to give limited access to the tray, both covers being removable bodily as a unit with the carrier.

45 12. In a photographic developing apparatus, the combination with a tray having a print receiving end and a print delivery end, of a quickly and easily removable and replaceable carrier associated with the tray, a cover panel on the carrier covering the body of the tray, a cover hinged to the carrier at the delivery end of the tray and adapted to give limited access to the tray, both covers being removable bodily as a unit with the carrier, and a print feeding device on the latter also removable bodily as a unit therewith.

50 13. In a photographic developing apparatus, the combination with a tray having a print receiving end and a print delivery end, of a quickly and easily removable and replaceable carrier associated with the tray, a cover panel on the carrier covering the body of the tray, a cover hinged to the carrier at the delivery end of the tray and adapted to give limited access to the tray, both covers being removable bodily as a unit with the carrier, and an immersing guide for the prints mounted on the carrier in spaced relationship to the bottom of the tray and also removable as a unit with the carrier.

55 14. In a photographic developing apparatus, the combination with a tray having a print receiving opening at one end and a print delivery opening at the other end, and a cover panel light sealing the body of the tray, of an independently displaceable lid for the delivery opening and a quickly and easily detachable and replaceable carrier cooperating with the tray and supporting the lid and cover so that the last two mentioned elements may be removed bodily as a unit therewith for access to the interior of the tray.

60 15. In a photographic developing apparatus, the combination with a covered tray having a print receiving opening at one end and a print delivery opening at the other end, of an independently displaceable lid for the delivery opening, a detachable and replaceable carrier cooperating with the tray and supporting the lid, and a print submerging guide in the tray mounted on and removable as a unit with the carrier.

65 16. In a photographic developing apparatus,

5   tus, the combination with a covered tray having a print receiving opening at one end and a print delivery opening at the other end, of an independently displaceable lid for the delivery opening, a detachable and replaceable carrier cooperating with the tray and supporting the lid, and a print feeding device in the tray mounted on and removable as a unit with the carrier.

10   17. In a photographic developing apparatus, the combination with a covered tray having print receiving and print delivery openings at opposite ends and a print feeding device operating within the tray, of a hinged

15   lid for the delivery opening having a limited opening movement, an inclined guide for the print beneath the lid having a depression therein, and a stop for the advancing edge of the print depending from the lid and normally occupying the depression in the guide.

20   18. In a photographic developing apparatus, the combination with a covered tray having print receiving and print delivery openings at opposite ends and a print feeding device operating within the tray, of a hinged

25   lid for the delivery opening having a limited opening movement, an inclined guide for the print beneath the lid, a pivoted stop for the advancing edge of the print depending from the lid and normally cooperating with the guide, and means contacting with the stop for swinging it rearwardly away from the incline of the guide as the lid is raised.

30   19. In a photographic developing apparatus, the combination with a covered tray having print receiving and print delivery openings at opposite ends and a print feeding device operating within the tray, of a hinged

35   lid for the delivery opening having a limited opening movement, an inclined guide for the print beneath the lid, a pivoted stop for the advancing edge of the print depending from the lid and normally cooperating with the

40   guide, a fixed abutment for swinging the stop rearwardly away from the incline of the guide as the lid is raised and a slotted link on the lid cooperating with the abutment to limit the raising movement of the lid.

45   20. In a photographic developing apparatus, the combination with a covered tray having print receiving and print delivery openings at opposite ends and a print feeding device operating within the tray, of a hinged

50   lid for the delivery opening having a limited opening movement, an inclined guide for the print beneath the lid, and a squeegee roller mounted in sliding bearings on the under side of the lid to cooperate with the lip of

55   the delivery opening so that when the lid is closed the weight of the roller only rests upon the print.

60   21. Photographic developing apparatus comprising a covered tray having print receiving and print delivery openings, print

65   feeding means operating within the tray, a hinged lid adjacent the delivery opening, abutment means for limiting downward movement of said hinged lid, a pair of slotted bearings depending from the under side of said lid, and a roller mounted in said slotted bearings in position to rest upon a print being withdrawn from said delivery openings, said roller being capable of limited upward and downward movement when said hinged
